UNITED STATES PATENT OFFICE

JUSTIN F. WAIT, OF NEW YORK, N. Y., ASSIGNOR TO SUN OIL COMPANY, OF PHILADELPHIA, PENNSYLVANIA, A CORPORATION OF NEW JERSEY

APPARATUS FOR TRANSFERRING HEAT

Application filed August 8, 1925. Serial No. 48,987.

My invention relates to an improved method and apparatus for transferring heat from a source to a point of use.

More particularly my invention relates to an improved method for the transfer of heat through the medium of metallic vapors, for example, of mercury, cadmium, zinc and the like or mixtures thereof and to heating apparatus of improved design and great efficiency.

Heretofore heat transference through the medium of metallic vapors has been accomplished by various methods and by the use of various apparatus. However, while results of substantial practical value have been obtained, such methods and apparatus as have been used have not proved entirely satisfactory and have been open to numerous objections, chief among which are that the efficiency of the metallic vapors is decreased by the presence of entrained metal and that the flow of the vapors is retarded by accumulations of scale, oxide and other impurities present in the apparatus or carried therein by the vapors.

Now, it is the object of my invention to provide a method and apparatus for the utilization of metallic vapor as a heat transfer medium with maximum efficiency and by which the vapors will be freed from entrained metal and from solid impurities accumulation of which tend to retard the flow of the vapors. Further objects of my invention are to provide means for accurately controlling the pressure and flow of the metallic vapors in the apparatus to the end that they may be utilized with maximum efficiency.

Having indicated, in a general way, the nature and purpose of my invention, I will now proceed to a detailed description thereof with reference to the accompanying drawings in which is illustrated a form of apparatus embodying my invention in so far as it relates to details of construction and which may be utilized for carrying out the method embodying my invention, though it will be understood that the practice of my method is not dependent upon the use of any particular form of apparatus.

Referring now to the drawings in which:

Figure 1 is a diagrammatic view of an apparatus for effecting heat transference through the medium of metallic vapors.

Figure 2 is a sectional view of a separator included as an element in the apparatus shown in Figure 1.

Figure 3 is a sectional view of a vapor flow control device included as an element in the apparatus shown in Figure 1.

Figure 4 is a sectional view of a modification of the subject of Figure 3.

Figure 5 is a side view, partly broken away and partly in section, of a heater included as an element in the apparatus shown in Figure 1.

Figure 6 is a view showing a detail of construction of the subject of Figure 5.

Figure 7 is a sectional view showing a detail of construction of the subject of Figure 5.

Figure 8 is a sectional view of a vapor pressure control device included as an element in the apparatus shown in Figure 1.

The apparatus consists essentially of a heating element comprising a chamber 3 from which depend fingers 29 intermediately divided by vertical tubular partitions 36 to form passages within the fingers in communication with the chamber 3 at their upper ends and with each other at their lower ends through apertures formed in the partitions. The heating element, or heater, is suitably mounted in brick work and is adapted to be heated by the application of heat about the fingers 29. The heating element is charged with metal, as mercury, cadmium, zinc, etc., or mixtures thereof, for example, to a level in chamber 3 indicated by the broken line 35 in Figures 1 and 7. On the application of heat, the metal circulates through the passages, formed in the fingers, to and from the chamber 3 and vapors arising from the metal collect in the upper portion of the chamber, being led therefrom through a pipe 4. The heated metal circulating to and from the chamber 3 passes downwardly into the fingers at increasing velocity and upward with relatively high velocity, which decreases on the passage of the metal into the chamber, thus permitting flotation of solid impurities, such as oxide, scale, etc., which may be mixed with

100

the metal. An aperture 33, provided with a suitable closure, is provided in the end of the chamber 3 at a level permitting removal of impurities from the surface of the metal in the chamber.

- 5 The pipe 4, which leads from the top of chamber 3 and which serves as a passage for metallic vapors therefrom, is connected to a vapor flow control device which consists of a chamber 19 into which, from its top, an end portion of pipe 4 projects. From adjacent the top of chamber 19 a pipe 18 leads to a heat absorbing unit 5, illustrated as a coil within a chamber, which may contain material to be heated and which will absorb heat from metallic vapors in the coil. From the bottom of the chamber 19 a pipe extends downwardly and upwardly, its end being connected to the bottom of a second chamber 21, provided with cooling flanges 25, and from which a pipe 22, an end portion of which extends upwardly within the chamber, leads to a separator 7b. A pipe 23 is connected to the chamber 21 at its top. Chamber 21 forms a means whereby the flow of vapor from heater 3 to heat exchanger 5 may be controlled. In the operation of the control device, the chamber 21 and the pipe leading therefrom to chamber 19 are filled with a metal 26 similar to that in the heating element, for example, mercury. The level of the metal in chamber 21 is controlled by pipe 22. The chamber 21 is positioned at a higher level than the chamber 19 and the metal is prevented from flowing from chamber 21 to chamber 19 by maintaining a pressure in chamber 21 such that liquid cannot normally rise in chamber 19 above the lower end of the pipe 4. The desired pressure may be maintained in chamber 21 by means of a pump α attached to the pipe 23. So long as the metal in chamber 21 is prevented from flowing into chamber 19, vapors issuing from pipe 4 will pass from chamber 19 through pipe 18 to the heat exchange coil 5. The vapors on entering chamber 19 will lose velocity and any entrained metal will be dropped therein. If it be desired to shut off the flow of vapors from pipe 4, such is accomplished by varying the pressure on the metal in chamber 21, which will cause it to flow into chamber 19 and form a liquid seal over the end of pipe 4.

In the modification shown in Figure 4, the chamber 21, containing metal 27, is positioned at a lower level than the chamber 19 and the metal 27 is caused to flow into chamber 19 to seal pipe 4 by the application of pressure through pipe 24.

The metallic vapors, which enter the heat exchange coil 5 are in part condensed therein and vapor and condensate flow from the coil through a pipe 6 to a separator 7. The separator comprises a chamber 7 to which pipe 6 is connected at a point between its top and bottom. Opposite to the point of connection

of pipe 6 a pipe 14 leading to a condenser 7a is connected. The vapor and condensate entering separator 7 are separated, the vapors passing out of the chamber to the condenser 7a and the condensate passing back to the heating element through a suitable pipe 8 leading from the bottom of the separator. A body of condensate is maintained in separators 7, 7b, 7c and 7d at the same level 35 as in the heater 3, and impurities therein are permitted to settle out by flotation. The separator 7 is provided with a removable cover 13, carrying a depending flange element 10 which enters a body of metal, as mercury, carried in a trough 11, formed adjacent the top of separator 7, to form a liquid seal. Impurities separated from the metal in separator 7 may be readily removed from time to time on removal of the top 13. The separators 7b, 7c and 7d are all similar to the separator 7.

Any metal which overflows from chamber 21, of the vapor flow control device, through pipe 22 enters a separator 7b similar to that described above, except that since no vapors enter it is vented to atmosphere instead of being connected to a condenser. The condensate from the condenser 7a, which receives vapors from the separator 7 which receives both vapor and condensate from the heat exchanger 5, passes to a similar separator 7d, vented to atmosphere and thence back to the heater.

In order that any excess pressure of vapors in the apparatus may be relieved, a safety device is provided which consists of a chamber 50 into which extends downwardly the end portion of a pipe 40 connected to vapor pipe 4. A body of metal, as mercury, is maintained in chamber 50 at a level above the end of pipe 40, the level being determined by an overflow pipe 42. A pipe 44 leads from the upper portion of chamber 50 to a condenser 45 in turn connected to a separator 7c such as has been described, vented to atmosphere and connected to the heater. In operation the metal in chamber 50 acts as a liquid seal in pipe 40, the amount of metal over the end of the pipe being sufficient to seal against normal pressure in the apparatus. If the pressure in the apparatus increases, vapors will force their way through the liquid seal in chamber 50 and the pressure will be relieved. The vapors will be condensed in condenser 45 and the condensate freed from impurities in the separator, returned to the heater.

Having now fully described my invention, what I claim and desire to protect by Letters Patent is:—

1. In a heating apparatus, in combination, a heater adapted for the vaporization of a metal, a heat exchanger, a conduit for the passage of vapors from the heater to the exchanger, and means for limiting the pressure of vapors in said apparatus comprising a sec-

ond conduit receiving vapors from said apparatus and having an outlet controlled by a liquid metal seal.

2. In a heating apparatus, in combination, 5 a heater adapted for the vaporization of mercury, a heat exchanger, a conduit for the passage of vapors from the heater to the exchanger, and means for limiting the pressure of vapors in said apparatus comprising a second conduit receiving vapors from said apparatus and having an outlet controlled by a mercury seal.

3. In a heating apparatus, in combination, 15 a heater adapted for the vaporization of a metal, a heat exchanger, a conduit affording a passage for vapors from the heater to the heat exchanger, a second conduit receiving vapors from the heater, a chamber into which said second conduit extends, a body of liquid 20 metal in said chamber, means to maintain the level of said body of liquid metal above the outlet end of said second conduit a distance sufficient to prevent the discharge of vapors therefrom under predetermined pressure and 25 an outlet from said chamber above the level of the liquid metal therein.

4. In a heating apparatus, in combination, 30 a heater adapted for the vaporization of a metal, a heat exchanger, a conduit affording a passage for vapors from the heater, a chamber into which the outlet end portion of said conduit extends and a conduit for the passage of vapors from said chamber to the heat exchanger.

35 5. In a heating apparatus, in combination, a heater adapted for the vaporization of a metal, a heat exchanger, a conduit affording a passage for vapors from the heater, a chamber into which the outlet end portion of said conduit extends, a conduit for the passage of vapors from said chamber to the heat exchanger, means affording a supply of liquid metal to said chamber in quantity sufficient to afford a seal for the outlet end of said first mentioned conduit and means for controlling the supply of metal in said chamber.

60 6. In a heating apparatus, in combination, a heater adapted for the vaporization of a metal, a heat exchanger, a conduit affording a passage for vapors from the heater, a chamber into which the outlet end portion of said conduit extends, a conduit for the passage of vapors from said chamber to the heat exchanger, a second chamber, a supply of liquid metal in said second chamber, a conduit affording communication between said chambers and means connected to said last mentioned chamber whereby the pressure therein may be equalized with that within said first mentioned chamber or differentiated therefrom to effect transfer of said liquid metal from one chamber to another.

65 7. In a heating apparatus, in combination, a heater adapted for the vaporization of a metal, a heat exchanger, a conduit affording

a passage for vapors from the heater to the heat exchanger, a condenser, a separator, a conduit connecting the heat interchanger with the separator, a conduit connecting said separator with the condenser and a conduit 70 connecting said separator with the heater, said separator being adapted to permit liquid metal to separate from vapors and to permit the separation of solid impurities from the liquid metal by flotation.

In testimony of which invention, he has hereunto set his hand, at New York, New York, on this 6th day of August, 1925.
